UNITED STATES PATENT OFFICE.

CHARLES SCHUSSLER, OF BLUE ISLAND, ILLINOIS.

CAR-DOOR OPENING AND CLOSING MECHANISM.

Application filed October 4, 1926. Serial No. 139,543.

This invention relates to opening and closing mechanism for sliding doors and more particularly for railway car doors.

One object of my invention is to provide 5 a mechanism which may be readily and easily applied to each door of a car and thus have the car carry as a part of its regular equipment an opening and closing mechanism for each of its doors so that the latter 10 may be readily and easily opened or closed without the use of crow-bars or other prying devices to do damage or injury to either the door, or the car wall as heretofore.

Another object of my invention is to provide 15 the mechanism with two sets of teeth and an actuating means therefor mounted on the door and the associated car wall respectively with the actuating means engageable with either set of teeth for respectively opening and closing the door through the medium 20 of said teeth.

A further object of my invention is to arrange the teeth in rows extending cross-wise of the door and have the actuating means in 25 the form of an endwise movable member or bar with a shoe having an intermittent pushing action on the teeth of one set to close the door and an intermittent pulling action on the teeth of the other set to open the door 30 in the respective backward and forward movements of the bar.

A still further object of my invention is to provide means for locking the shoe in engagement with the teeth of the set employed 35 to close the door when the latter is closed and thus provide a rigid and secure lock which will not break or allow the door to accidentally open, thereby making it unnecessary to spike the door to keep it closed as 40 with the easily breakable locks as heretobefore used.

A further object of my invention is to provide a mechanism which is simple in construction and operation and which may be 45 readily reached for repair or such other attention as it may require without taking down either the door or the car wall or in any way damaging or injuring the same.

The invention consists further in the mat- 50 ters hereinafter described and claimed.

In the accompanying drawings—

Fig. 1 is a side elevational view of an opening and closing mechanism constructed in accordance with my invention and shown 55 applied to a car door;

Figs. 2, 3 and 4 are enlarged vertical sec-

tional views taken on lines 2—2, 3—3 and 4—4 respectively, of Fig. 1, to show various details of construction; and

Fig. 5 is an enlarged side elevational view 60 of the racks, actuating shoe and lock therefore.

In the drawings, 1 indicates one of the side walls of a freight car, 2 the door opening 65 therein, and 3 the sliding door for said opening. The hangers 4, 4 at the upper edge of the door carry rollers (not shown) which run on a suitable rail or track 5 secured to the car wall along the upper edge of the door so that the latter may be slid open and 70 closed as in structures of this kind.

The door opening and closing mechanism of my invention is constructed as follows. A pair of metal racks 6, 7 are secured on the 75 outside of the door 3 by bolts 8, 8. These racks extend cross-wise of the door below the middle thereof and are vertically spaced apart with their teeth 9, 9 opposed. The racks 6, 7 extend outward from the door 3 substantially the same distance and have the 80 space between them closed along the length of the racks by a cover plate 10 which is secured against the outside of the racks by the same bolts 8 used to secure the racks to the door, as shown in Fig. 2.

An actuating member in the form of a bar 11 extends into the space between the racks 6, 7 from the rear edge of the door, as shown in Fig. 1. The bar 11 carries a shoe 12 at its front end. Said shoe is vertically 90 disposed so as to extend above and below the bar and engage either set of teeth 9 for respectively opening and closing the door.

The bar 11 extends rearward from the door along the outside of the car wall 1 in alignment with the space between the racks, 6, 7 as shown in Fig. 1. At the rearward end of the bar there is a hand operating lever 13 pivoted near its upper end to the car wall 1 by a bolt 14 as shown in Fig. 4. The upper end of the lever 13 is pivoted to the bar 11 near its rear end by a bolt 15, and a spacer 16 is on the bolt 14 between the lever and the car wall 1 to hold the bar and lever 11 and 13, respectively, out of contact with the car wall, as shown in said Fig. 4.

The greater length of the bar 11 being in advance of the hand lever 13, the weight of the bar normally holds the shoe 12 against the teeth of the lower rack 7, as shown in 115 Figs. 1 and 5. It is to be noted from these figures that the teeth 9 of both racks have

vertical faces *a* and inclined or slanting faces *b*. The teeth of the two sets are disposed with their vertical faces *a* facing in opposite directions, those of the upper set 5 facing the front edge of the door 3 while those of the lower set face the rear edge of the door with the inclined faces *b* between them and facing downward and upward respectively.

10 The upper and lower ends of the shoe 12 are made complementary to the teeth of the racks and thus have vertical and inclined faces *c*, *d*, respectively. The vertical faces *c* of the shoe are on the front and rear sides, 15 respectively, of the shoe so as to engage the vertical faces *a* of the teeth 9 of the respective racks for opening and closing the door, while the inclined faces *d* of the shoe permit the same to ratchet over the inclined 20 faces of the teeth 9 when sliding the shoe over the same.

In operation, the operator grasps the lever 13 and swings the same laterally back and forth on its fulcrum 14, as indicated by the 25 dotted lines in Fig. 1, thereby causing the bar 11 to be moved endwise back and forth with respect to the car wall 1. When closing the door, as in Fig. 1, the shoe 12 is allowed to rest on the lower rack 7. On each forward 30 movement of the bar 11, the vertical face *c* at the lower front end of the shoe engages in front of one of the teeth 9 and pushes the door toward its closed position. On each rear stroke of the bar, the shoe 11 rides or 35 ratchets back over a few teeth and engages behind another one for another forward push. These operations are repeated until the door has been moved by the bar into 40 fully closed position, each movement of the door being a few teeth at a time.

To open the door, the operator in addition to moving the lever 13 as before presses down on the rear end of bar 11 or lifts up on the bar in front of the lever 13 to raise 45 the shoe 12, into engagement with the teeth 9 of the upper rack 6, the shoe at this time being free of the teeth of the lower rack, as shown in dotted lines in Fig. 5. On each forward stroke of bar 11, the shoe 12 ratchets forward over the inclined faces of the teeth of the upper rack while on each rearward stroke the vertical face *c* at the upper side of the shoe hooks behind a tooth and serves to pull the door towards its open position. 50 These operations are repeated until the door is fully open, the shoe intermittently engaging the rack as before and moving the door a few teeth at a time on each rearward stroke of the bar 11.

60 To lock the door 3 closed, I provide a locking member 17 pivoted at one end by a bolt 18 to the rear side of an arm 19 at the rear end of the upper rack 6, as shown in Figs. 1 and 5. The arm 19 extends beyond 65 the rear end of the lower rack so that the

locking member may engage the bar 11 exterior of the racks. As shown in Fig. 3, the member 17 is so shaped that when in locking position its free end *e* extends downward across the bar 11 in front of the same 70 to prevent the shoe 12 from being moved outward from the teeth of the lower rack 7 should the plate 10 be removed. The mid-portion *f* of the member 17 extends 75 across the top of the bar 11 to prevent the latter from being lifted to free the shoe 12 from the teeth of the lower rack. To secure the bar 11 and member 17 in these positions, I pass a wire or band 20 of a car seal 21 through registering holes in the parts and 80 secure the two ends of the wire in the seal 21 as shown in Fig. 3. To unlock the door 3 so that it may be opened, the seal wire is cut and withdrawn from the holes in the bar 11 and member 17 whereupon the latter 85 may be swung up on top of the upper rack 6 to be out of the way as shown in Fig. 1.

The shoe 12 is preferably made separate from the bar 11 and afterwards secured thereto by bolts or screws 22, 22 as shown 90 in Fig. 5. For this purpose the shoe has a shank 23 which fits against the bar 11, the latter being preferably made channel shaped as shown in Fig. 2. By providing the shank 23 and bar 11, where they engage, 95 with a plurality of bolt holes, the shoe may be adjusted lengthwise of the bar 11 to position the shoe for the teeth of the racks. Moreover, by this construction the shoe may be removed from the bar 11 when worn and 100 be replaced by a new one.

With my improved mechanism, the door may be readily and easily slid back and forth by merely moving the hand lever 13 and seeing that the shoe 12 engages the 105 proper set of teeth. With the actuating means having an intermittent grip and release action on the door in opening and closing it, a series of relatively short power strokes may be employed at the expenditure 110 of far less power than heretofore required, thereby allowing the door to be opened or closed without undue effort. The cover plate 10 not only serves to prevent the shoe 12 from leaving the space between the racks 115 but also protects the same from the weather as well as dust and dirt. The hand lever 13 will be spaced far enough from the door to allow the door to be moved toward the same to fully open position without interference by the hand lever. Moreover, the bar 11 will be long enough to have its shoe 12 remain engaged with the teeth of the respective racks whether the door is fully open 120 or fully closed, thus enabling the shoe to act 125 on the door in any position thereof.

The details of structure shown and described may be variously changed and modified without departing from the spirit and scope of my invention.

I claim as my invention.

1. The combination with a car wall having an opening and a sliding door therefor, of an opening and closing mechanism for said door, consisting of a pair of upper and lower racks extending crosswise of the door and secured thereto with their teeth opposed, a hand lever pivoted to the car wall at one side of the door, and an endwise movable 10 actuating member pivoted to the hand lever at one end and having at its opposite end a shoe between the racks and engageable with the teeth of either of them for respectively opening and closing said door thereby.
- 15 2. The combination with a car having an opening and a sliding door therefor, of an opening and closing mechanism for said door, consisting of upper and lower racks extending cross-wise the door and secured 20 hereto with their teeth opposed, a hand lever pivoted to the car wall at one side of the door, and an endwise movable bar pivoted at one end to said hand lever and having at its opposite end a shoe between the 25 racks, said shoe having its upper and lower ends engageable with the teeth of the respective racks with the ends of the shoe and the teeth having complementary vertical faces, facing in opposite directions so that the shoe 30 may be pushed against the teeth of one rack to close the door and pulled against the teeth of the other rack to open the door.
3. The combination with a car wall having an opening and a sliding door therefor, of an opening and closing mechanism for said door, consisting of a pair of upper and lower racks extending cross-wise of the door and secured thereto with their teeth opposed, a hand lever pivoted to the car wall at one 35 side of the door, an endwise movable member pivoted at one end to said lever and having at its opposite end a vertically disposed shoe having its upper and lower ends engageable with the teeth of the respective 40 racks for opening and closing the door thereby, and locking means for holding the shoe engaged with the door opening rack when the door is closed.
- 45 4. The combination with a car wall having an opening and a sliding door therefor, of an opening and closing mechanism for said door, consisting of a pair of upper and lower racks extending cross-wise of the door and secured thereto with their teeth opposed, a hand lever pivoted to the car wall at one side of the door, an endwise movable bar 50
- 55

pivoted at one end to said lever and having at its opposite end a shoe engageable with the teeth of either of the racks for opening and closing the door thereby, and a member 60 pivoted to one rack and lockable to the bar for holding the shoe engaged with the door opening rack when the door is closed.

5. The combination with a car wall having an opening and a sliding door therefor, of an opening and closing mechanism for said door, consisting of a pair of upper and lower racks extending cross-wise of the door and secured thereto with their teeth opposed, a hand lever pivoted to the car wall at one 65 side of the door, an endwise movable bar pivoted at one end to said hand lever and having at its opposite end a shoe between the racks and engageable with the teeth of either of the same for opening and closing 70 the door therethrough, a locking member pivoted to the upper rack and having a right angled portion to extend over the top and outer side, respectively, of the bar to hold the shoe engaged with the door open- 75 ing rack when the door is closed, said member and bar having registering opening to receive a fastening wire.

6. The combination with a car wall having an opening and a sliding door therefor, of a door opening and closing mechanism for said door, consisting of a pair of upper and lower racks secured to the door on the exterior thereof and extending cross-wise of the same with their teeth opposed, a plate 90 covering the space between the racks and secured thereto, a hand lever pivoted to the car wall to the rear side of the said door, and an endwise movable member pivoted to said lever and extending into the space between the racks behind the plate and there having a shoe engageable with the teeth of either rack for opening and closing the door 95 thereby.

7. The combination with a car wall having an opening and a sliding door therefor, of an opening and closing mechanism for said door, consisting of a pair of upper and lower racks extending crosswise of the door and carried thereby, and actuating means carried 100 by the car wall and engageable with the teeth of either rack for respectively opening and closing the door thereby.

In testimony whereof I affix my signature this 30th day of September, 1926.

CHARLES SCHUSSLER.
